UNITED STATES PATENT OFFICE.

ERNST J. ERICSEN, OF NEW YORK, N. Y.

SCREEN AND PORTABLE CASING THEREFOR.

Application filed January 28, 1925. Serial No. 5,200.

The improvements relate to screens for windows and other openings, and their objects are among others to provide a window or other opening with a screen having a removable casing, which may be readily removed and replaced; to so construct and mount the screen therein that it will slide up and down and remain in any desired position; to provide for the easy removal and replacement of the screen, and to render the operation of raising and lowering the screen easy.

The improvements are illustrated in the accompanying drawings, in which Fig. 1 is a perspective view of a portion of a window frame with sashes therein, and of a casing and screen mounted therein embodying the improvements;

Figs. 2 and 3 are end views of the casing members;

Figs. 4 and 5 are side elevations of the parts shown in Figs. 2 and 3 showing the side next to the screen;

Fig. 6 is a front side view of the screen; and Fig. 7 is an edge view thereof.

In the illustrative embodiment of the improvements, the screen and the casing are shown mounted inside the sashes of an ordinary glass window and on the inner side of the frame 5 thereof. 1 represents the casing of the sash which may be of identical construction on both sides, and in each case consists of a piece of sheet metal or the like having an outwardly turned longitudinal flange 1^a by which it may be fastened to the window frame by means of small screws or other fastenings passed through the holes 1^b therein, a hollow angular portion 1^c, a U-shaped portion 1^d in which the screen frame slides and another longitudinal flange 1^e with holes 1^f through which nails or the like may be passed to secure it to the strip 7. The casing members are made in two sections connected by a hinge 2, and a hook 14 and eye 15 are mounted one on each section near the hinge so that when the lower part of said casing is swung up on its hinge it can be hooked so that it will remain in raised position.

50 A pulley 4 is mounted on the inside of the casing, and the cord 6 passes through the opening 1^g over the pulley to the weight 9 on the inside and to the sash 3 on the outside thereof, where it engages the frame by means 55 of a hook or any other suitable device se-

cured to one end thereof and entering the recess 8 of the said screen frame.

The cord is secured to the screen frame a distance below the top corresponding with the distance between the pulley and the top 60 of the casing, so that the screen may be moved to its uppermost position at the top of the window opening and above the hinge 21 which enables the user to swing the casing members out on their hinges and then slide 65 the screen down and remove it. It also permits the screens to be moved to the top of the window when not in use. It will further be seen that by providing the screen with the cord and weight it is easily raised, and will 70 remain in any position to which it may be moved, so that the window may be opened or closed, or for other purposes.

An ordinary small knob or handle 10 on the bottom of the screen frame is provided 75 for the purpose of moving it.

To the top bar of the frame of the screen 3 a rail 11 extending therefrom in the direction of the window sash is secured by means of hinges 12, and this serves the purpose of closing the crack between the screen and the horizontal rail of the lower sash 13. The improvements are well adapted to be used with or without the weight and cord if desired, and when so used, will be found 85 to possess many advantages over the similar devices commonly employed.

What I claim is:

1. A casing member adapted to guide a 90 slideable frame comprising a sectional housing having aligned portions adapted to be engaged by a frame for sliding movement thereon, the sections of said housing being pivotally connected for relative arcuate travel, an antifriction member mounted on 95 one of said sections whereby to cooperate with a counterbalancing member for a sliding frame, said housing constructed and arranged to house such counterbalancing member.

2. A casing member adapted to guide a 100 slideable frame comprising a sectional housing having aligned portions adapted to be engaged by a frame for sliding movement thereon, the sections of said housing being 105 pivotally connected for relative arcuate travel, and each of sufficient extent to house a sliding frame independent of its companion section, and means for supporting said sections in relative angular position, the 110

construction and arrangement being such whereby a sliding frame may be moved onto a section of the housing and such section temporarily swung and held out of alignment with its companion section. ¹⁵

3. A casing member adapted to guide a slideable frame comprising a sectional housing having aligned portions adapted to be engaged by a frame for sliding movement thereon, the sections of said housing being operatively associated for relative movement,

Witness my hand this 22nd day of January, 1925, at the borough of Manhattan, in the city, county and State of New York.

ERNST J. ERICSEN.
